UNITED STATES PATENT OFFICE.

EARL V. COULSTON, OF ROCK ISLAND, ILLINOIS, ASSIGNOR TO ROCK ISLAND STOVE COMPANY, OF ROCK ISLAND, ILLINOIS, A CORPORATION OF ILLINOIS.

STOVE OR FURNACE.

1,008,698.

Specification of Letters Patent. Patented Nov. 14, 1911.

Application filed January 13, 1908. Serial No. 410,586.

To all whom it may concern:

Be it known that I, EARL V. COULSTON, a citizen of the United States of America, and resident of Rock Island, Rock Island county, Illinois, have invented a certain new and useful Improvement in Stoves or Furnaces, of which the following is a specification.

My invention relates to stoves or furnaces of that character in which an interior air flue is employed, and in which the fire pot is arranged intermediate the ash pit or base and the upper stove body within which the said flue is inclosed.

Generally stated, the object of my invention is the provision of an improved and highly efficient stove of this general character.

Special objects are the provision of an interior air flue of improved formation, whereby the hot gases and products of combustion are retained in contact with the face thereof until the same reach the top of the stove, and whereby the heating capacity of the stove is increased; the provision of a stove which, although adapted for burning the cheaper grades of fuel, is still and nevertheless capable of radiating considerable heat from its base or ash pit below the fire pot, thus still further increasing the heating efficiency of the stove; the provision of an improved construction of the fire pot, whereby the air is caused to pass down and then up through the side walls of the fire pot, before being allowed to enter the sides of the body of burning fuel, and before being allowed to escape over the top of said fuel, thus insuring the highest degree of combustion at a point immediately above the said bed of fuel; to improve the combustion in a stove in which the air is more effectively heated before passing to the flue which has its lower end coupled to a flat or flattened surface of the body to give increased width to the said flue, and increased heating capacity; and the provision of certain details and features of improvement and combinations tending to increase the general efficiency and serviceability of a stove of this particular character.

To the foregoing and other useful ends, my invention consists in matters hereinafter set forth and claimed, but it will be

understood that I do not wish to be unduly or unnecessarily limited to the construction disclosed for producing the desired results.

In the accompanying drawings—Figure 1 is a vertical section of a stove, embodying the principles of my invention. Figs. 2, 3 and 4 are fragmentary sectional views of the fire pot construction. Fig. 5 is a cross section of the inner air flue, showing a modified form thereof. Fig. 6 is a cross section on line 6—6 in Fig. 1. Fig. 7 is a cross section on line 7—7 in Fig. 1. Fig. 8 is a cross section of the inner flue on line 8—8 in Fig. 1. Fig. 9 is a detail vertical section of one side of the fire pot on line 9—9 in Fig. 1. Fig. 10 is an upper end view of the flue. Fig. 11 is a lower end view of said flue.

As thus illustrated, my invention comprises a stove body A, which is preferably square or rectangular in cross section, as shown more clearly in Fig. 6. This stove body has a top a provided with the usual opening a¹ for a stove pipe or smoke flue. The said top is also provided centrally with a round opening a², for the upward discharge of heated air, as will hereinafter more fully appear. At its front the said stove body has a door a³, whereby fuel can be fed to the combustion chamber. The said stove body is supported upon the fire pot B, and an upper casting C is supported upon the top of said fire pot and inclosed or engaged all around by the sides of the stove body. A hollow base D is provided for supporting the said fire pot, said base being provided with suitable legs d, if such are desired. At the front of the stove a damper or air inlet E is provided, whereby air may enter and circulate between the outer surface of the casting C and the inner surface of the stove body, as indicated. The flat back of the stove has an air inlet or opening a⁴, and this opening is connected by an interior flue F with the upper opening a², in the manner illustrated. In this way the said flue F is disposed over the fire pot, and is adapted to discharge highly heated air from the top of the stove. As the back of the stove is flat, the opening a⁴ can be considerably wider than it is high, and in this way the flue F can be as wide as desired, its lower end being coupled flatwise over the

opening a^4 , so that no difficulty is encountered in making the connection, regardless of the width of the said opening and flue.

If desired, the opening a^2 in the top of the stove can be round, as shown in Fig. 10, and in such case the said flue F will be round at its upper end and flattened at its lower end, as indicated in Fig. 1. Fig. 11 shows the way in which the lower end of the flue 10 is broadened and flattened. The opening a^4 is thus necessarily oblong, being broader than it is high, so as to match the opening in the lower end of the flue. See Fig. 11. In other words, the sides of the said flue near 15 its lower end can be made narrower than its face or under surface, so that its elbow f does not extend too far over the fire pot and is not likely to be burned out or become destroyed more quickly than the other parts 20 of the stove. The broadening of the flue in this manner provides it with a flat or substantially flat face f^2 , and this face can be provided with corrugations f^3 , as shown more clearly in Fig. 8. If desired, the face 25 of said flue can be provided with one broad channel f^4 , as shown in Fig. 5; but in either case the face of the flue is so formed that the heat and products of combustion are held in contact with the flue until they reach 30 the top of the stove, thus increasing the heating capacity of the stove. In other words, with a flue with a perfectly flat or round front surface, the heat and products of combustion would strike it and immediately 35 pass around and behind the flue, and then escape upwardly through the stove pipe. With my improved formation of the flue, however, the hot gases and products of combustion are retained in contact with 40 the face of the flue until they reach the top of the stove, and thus the air within the flue is given a higher degree of heat than was heretofore possible in stoves of this character.

45 At the back of the stove, the concave shell G is bolted or otherwise secured thereto, its lower end being open, and its upper end being coupled flatwise over the opening a^4 , as illustrated. In this way the air near the 50 floor is permitted to rise through the broad flue provided by the shell G, and is therein heated by coming in contact with the fire pot B. After this the air passes through the opening a^4 and then upwardly through the 55 flue F, and finally passes out through the opening a^2 , where it can either be allowed to escape into the room, or conducted to another room above, as by the flue X indicated in dotted lines. Any suitable means can be 60 provided for regulating the discharge of heated air from the top of the stove—that is to say, from the upper end of the said interior flue. The said fire pot is provided with outer vertical air passages b which are 65 open at top and bottom, the upper ends

thereof communicating with the circulating chamber c outside of the casting C. The lower ends of said passages b communicate with the interior of the ash pit within the base D, and from this lower chamber d the air then passes upwardly through the bottom of the fire pot and into the fuel. The said fire pot also has its side wall provided with vertical air passages b^1 , which are open at their lower ends and closed at their upper ends. Each air passage b^1 is, however, provided at its inner side with a vertical slot b^2 , whereby the air entering at the lower ends of these passages can pass upwardly and into the sides of the body of fuel, and also to a point where the air can escape across the top of the burning bed of fuel. The air passages b can be formed by walls cast integral with the fire pot, or they can be formed by concave shells b^3 suitably fitted closely to the outside of the fire pot as shown more clearly in Figs. 3 and 4. With either construction, however, it will be seen that cold air enters through the damper or opening E, and then passes down through the passages b , thereby becoming heated before entering the ash pit or heating chamber d. This heated air then passes upwardly through the body of burning fuel and also across the top of the same, thus materially promoting combustion and increasing the heating efficiency of the stove. With a fire pot of this construction, the cheaper grades of fuel can be used, without danger of clogging in any of the passages or flues, and without resorting to constant cleaning of said flues or passages. Furthermore, and notwithstanding that the stove is adapted for burning the cheaper grades of fuel, the base D is utilized for radiating heat, as the air before entering the ash pit is highly heated, and in this way the heating efficiency of the stove is still further increased. A greater part of the air passes from the ash pit upwardly through the passages b^1 , and across the top of the fuel, so that the solid fuel burns slowly, thus generating gases, and the principal fire is due to the combustion of gases and volatile matter above the coal. In this way, the intense heat or highest degree of combustion is brought close to the flue F, with the result that the air passing upwardly through this flue is super-heated to a degree heretofore never accomplished. It will be seen that the supply of oxygen for promoting combustion is twice conducted through the highly heated walls of the fire pot, first down and then up, and that as a result the air which finally enters the bed of fuel, and which finally passes above the bed of burning fuel, is of a character to best promote combustion.

The casting C can be made in one piece, or in any suitable manner, according to requirements. There can be as many passages b as may be found requisite or desirable,

there being four of these flues shown in the drawings, one at each side of the fire pot.

The stove body A, as stated, is preferably square or rectangular, as such shape gives greater breadth to the flue F. It will be seen, however, that the feature of corrugating or channeling the face or front of the flue, so as to cause the hot gases and products of combustion to stay longer in contact therewith, can be employed in stoves of other shapes, without departing from the spirit of my invention. The novel fire pot construction herein disclosed can also be employed in stoves of other shapes without departing from the spirit of my invention.

As stated, the passages b in the fire pot, are, by reason of the construction employed, adapted for the downward passage of air therein, and the fire pot thus constructed is combined with draft producing means for accomplishing this desired result. It will be understood, of course, that such draft producing means may consist of the ordinary combustion chamber and stove pipe, whereby the upward movement of gases and products of combustion from the top of the stove serves to draw the air upwardly from the ash pit and through the fuel, thereby drawing the air downwardly through the outer passages in the fire pot—that is to say, the draft up the chimney allows atmospheric pressure to force air into the bottom of the stove. In other words, the said passages b are not only adapted for the downward passage of air therein, but are also combined with the general draft producing means of a stove whereby this result is actually accomplished. The air is first heated in the ample chamber around the top of the fire-pot, and then further heated by being brought downward outside of the fire-pot.

It will be seen that the fire pot is provided with vertically disposed air ducts or passages in the sides thereof, and with heat radiating surfaces intermediate the same. In this way ample heat is radiated from the sides of the fire pot, and at the same time air is taken downwardly through the sides of the fire pot, which air is thus heated before being discharged into the chamber below the fuel in the fire pot. For stoves and furnaces, the fire pot must be able to radiate heat from the sides thereof. With my improved construction the fire pot is capable of doing this, and at the same time heating a quantity of air for supporting combustion. Preferably, therefore, as illustrated, the heat radiating surfaces of the fire pot are arranged intermediate the ducts or passages through which the air is conducted downwardly to the chamber below the fuel. With my improved construction, the walls of the flues b and b¹ are imperforate, so that these flues or passages are only open at top and bottom, whereby no air can pass directly

therefrom to the interior of the fire pot. The entire volume of air must pass downward to the ash pit, before any air can enter the fire. In other words, no portion of the draft air is allowed to contact with the fire until after it has passed through the ash pit, or through the chamber below the fire pot. For the purpose of heating the air by the passage of the same downwardly at the sides of the fire pot, or of keeping the products of combustion in contact with the flue, and the combination thereof with the flattening of the body at the point where the lower end of the flue joins the back of said body, I do not limit myself to the exact construction shown and described.

What I claim as my invention is:

1. A stove or furnace having openings in the back and top thereof, a fire pot, an interior heating flue or air circulating chamber leading upwardly from the opening in the back of the stove to the opening at the top thereof, the face or front of said flue being inclined forwardly above the center of the fire-pot and channeled or corrugated longitudinally thereof to retain the hot gases or products of combustion in contact therewith until the same reach the top of the stove, as set forth.

2. A stove or furnace having openings in the back and top thereof, an interior heating flue or air circulating chamber leading upwardly from the opening in the back of the stove to the opening in the top thereof, said flue being round at its upper end and tapered downwardly when viewed from the side, but the face or front surface of said flue being broader than the sides thereof, and channeled longitudinally, as set forth.

3. In a stove or furnace, the combination of a fire-pot having its side walls provided with vertical air passages which are open at top and bottom and disposed at opposite sides of the fire-pot, an air circulating chamber at the top of the fire-pot communicating with the upper ends of said passages, said chamber being formed by a cap fitted on to the top of the fire-pot, means for admitting air to said circulating chamber, an ash pit below the fire-pot, and means for creating a draft to draw the air downwardly through said passages and into the ash pit, said air being then free to pass upwardly to the fuel in the fire-pot.

4. A stove or furnace comprising a fire-pot having the walls thereof provided with vertical passages which are open at top and bottom, and having other vertical passages which are closed at their upper ends and open at their lower ends, said additional passages having inner vertical slots communicating with the interior of the fire-pot, a chamber below said fire-pot communicating with the lower ends of all said passages, an air circulating chamber above the

fire-pot communicating with the upper ends of the said first-mentioned passages, and means for creating a draft upwardly above the fire-pot to cause air to pass downwardly through said first-mentioned passages, as and for the purpose set forth.

5. In a stove, the combination of a rectangular stove body having an opening in the back thereof, a fire pot, an interior flue 10 or air circulating chamber having its lower end coupled flatwise over the said opening, and means for conducting air upwardly to the said opening and into said flue, the said flue having its face inclined forwardly above 15 the center of the fire and corrugated or channelled longitudinally thereof to retain the hot gases and products of combustion in contact therewith until the same reach the top of the stove, as set forth.

20 6. In a stove, the combination of a body having an opening in the top and another in the back thereof, an interior flue or air heating chamber leading upwardly from the opening in the back of the stove to the opening in the top thereof, and a fire-pot below said flue or air circulating chamber, said fire-pot having vertical passages in the walls thereof for conducting air upwardly and discharging the same across the top of the 25 bed of fuel therein, whereby the principal point of combustion is above the fuel and immediately below said flue.

7. In a stove, the combination of a body having a flat back provided with an opening 30 therein, an interior flue having its lower end coupled flatwise over the said opening, an exterior shell applied to the stove to conduct the air upwardly to the said opening and into said flue, a fire-pot below said flue, an 35 ash pit or chamber below the said fire-pot, means for admitting air at the top of the fire-pot, said stove having passages for conducting air downwardly in contact with the fire-pot and into said ash pit or chamber 40 and passages in said fire pot for then conducting the air upwardly through the walls of the fire-pot and across the top of the fuel, whereby the principal point of combustion 45 is immediately below said flue.

50 8. In a stove, a fire pot, an interior air flue having its face or surface exposed to the fire formed with a channel or channels for keeping the upwardly moving gases and products of combustion in contact therewith.

55 9. In a stove, an inclined interior air flue therefor, disposed in position to permit circulation of the heat and products of combustion entirely around the same, corrugated 60 on the under surface thereof to keep the heat and products of combustion in contact therewith until the same reach the upper end thereof.

10. In a stove, an inclined interior air flue 65 therefor, with space all around the same,

longitudinally channeled on the under surface thereof to keep the heat and products of combustion in contact therewith, as set forth.

11. In a stove, an inclined interior air flue 70 therefor, means for delivering heated air to the lower end of said flue, a combustion chamber below the flue, and means in the sides of the combustion chamber for heating the air before the same passes upward from below and through the fire, said means having imperforate sides to prevent direct admission of air therefrom to the combustion chamber, and a square stove body inclosing said flue and to the flat back of which the 75 lower end of the latter is attached, giving increased width for the lower end of the flue, substantially as and for the purpose set forth.

12. In a stove, an inclined interior air flue 80 therefor, provided with a curved lower end, a combustion chamber below said flue, means for delivering heated air upwardly through said flue said air being for heating purposes, means for passing air downwardly 85 immediately outside of the fire, but not in contact therewith, to heat the air, and then upwardly through the fire, whereby the lower end of said flue is intensely heated, and a square stove body inclosing said flue and 90 to the flat back of which the lower end of the latter is attached giving increased width for the lower end of the flue, substantially as 95 and for the purpose set forth.

13. In a stove, an inclined interior air flue 100 therefor, provided with a curved lower end, a fire-pot below the same, means for admitting air upwardly through said flue, said air being for heating purposes, means for admitting air into the stove, said fire pot 105 having means for taking the air downwardly through the opposite sides of the fire-pot to heat the air, adapted to prevent any air from reaching the fire until after passing below the fire-pot, and then upwardly 110 through the fire, and a square stove body inclosing said flue and to the flat back of which the lower end of the latter is attached, giving increased width for the lower end of the flue, substantially as and for the purpose 115 set forth.

14. In a stove, a fire-pot having its side walls provided with exposed radiating surfaces and with air ducts or passages intermediate said surfaces, means for admitting 120 air to the upper ends of said air ducts or passages, each duct or passage having imperforate sides open only at top and bottom, and draft producing means operating to draw the air downwardly through said ducts 125 or passages.

15. In a stove, a fire-pot having side walls provided with exposed radiating surfaces and with air ducts or passages intermediate 130 said surfaces, each duct or passage having

- imperforate sides and open only at top and bottom, a chamber below the fire-pot communicating with the interior thereof, means for admitting air to the upper ends of said air ducts or passages, and draft producing means for drawing the air downwardly through said ducts or passages and into said chamber, whereby the air is heated before passing upwardly through the fuel.
16. In a stove, a fire-pot made of one integral piece of metal, provided with exposed and depressed radiating surfaces alternating with vertically disposed air ducts or passages spaced apart in the sides thereof, each duct or passage having imperforate sides and open only at top and bottom, means for admitting air to the upper ends of said ducts or passages, and draft producing means for then drawing the air upwardly through the fuel in the fire-pot.
17. In a stove, a fire-pot cast in one integral piece, having vertical passages in the sides thereof which are only open at top and bottom, and having other vertical passages which are closed at their tops and open at their lower ends, said last-mentioned passages being provided with vertical slots
- opening into the fire-pot, and means for feeding air to the passages which are open at their upper ends.
18. In a stove, a fire-pot provided with a vertically ribbed radiating surface, said ribs being hollow, means for feeding air downwardly through one or more of said ribs, means for then causing the air to ascend to the fire through one or more of said ribs, an air chamber one side thereof formed by a portion of said ribbed radiating surface, to preliminarily heat the air therein, a stove body with a flat or flattened back on said fire pot, an air flue in the stove body, above the fire pot, the lower end of said air flue being coupled by the flat back to the upper end of said air chamber, to give increased breadth to the lower end of said air flue, and means for supporting the upper end of the flue in the top of the stove.

Signed by me at Rock Island, Ill., this 21st day of Dec. 1907.

EARL V. COULSTON.
